Primary Examiner — Leanne Was-Englehart(74) *Attorney, Agent, or Firm* — Millman IP Inc.(57) **CLAIM**

The design for an insert for a door seal assembly, as shown and described.

DESCRIPTIONFIG. 1 is a perspective view from below, to the front and to one side of an insert for a door seal assembly;
FIG. 2 is a front view thereof, with a rear view being identical thereto;

FIG. 3 is a left side view thereof, with a right side view being identical thereto;

FIG. 4 is a top view thereof; and,

FIG. 5 is a bottom view thereof.

In the drawings, the broken lines shown in the figures represent boundaries of the claim as well as portions of the article which form no part of the claimed design. The break lines depict the bounds of the claim. The area between the break lines forms no part of the claimed design.
